UNITED STATES PATENT OFFICE.

JAMES J. LAWLER, OF PELHAM, NEW YORK.

EQUALIZING-VALVE FOR WATER.

1,076,293.

Specification of Letters Patent.

Patented Oct. 21, 1913.

Application filed January 17, 1912. Serial No. 671,641.

To all whom it may concern:

Be it known that I, JAMES J. LAWLER, a citizen of the United States, and resident of Pelham, in the county of Westchester and State of New York, have invented certain new and useful Improvements in Equalizing-Valves for Water, of which the following is a specification.

My invention relates to equalizing valves for water and is used on services where hot and cold water are combined and delivered at a predetermined temperature to any desired point, the object being to produce such a device in which air is heated or cooled, that is compressed or expanded for instantly and sensitively regulating the inlet valves.

Another object is to construct a compound valve, which controls a compound port through which the mixed hot and cold water passes, in such a manner as to avoid a "water hammer."

In my pending application, Serial No. 657,600, filed Oct. 30th, 1911, I show two separated valves in a valve body for regulating the supply of hot and cold water, and in the present application I make use of a double acting valve with a device adapted for use in special places where an extremely delicate or accurate degree of temperature must be continuously had.

In the drawings, wherein like reference characters denote corresponding parts in the several views, Figure 1 is a central vertical sectional view of the device, the compound or double acting valve being at its lowest point and open to the cold water. Fig. 2 is a cross sectional view on line 2—2 of Fig. 1. Fig. 3 is a center sectional view of the valve body, the two upper chambers being broken away, the compound valve and two check valves being shown in elevation and Fig. 4 is an end elevation of Fig. 3 partly shown in center section on line 4—4 of Fig. 2. Arrows indicate direction of the water.

The valve body, 1, is composed of a casting cored out in such a manner as to provide an inlet, 2, for cold water, a seating, 3, for a check valve, 4, an upper chamber, 5, an inlet for the hot water, 6, a seating, 7, for a check valve, 8, a lower chamber, 9, an inner chamber, 10, having an outlet 11: this inner chamber also has two ports in which the compound valve slides, the upper port, 13, is the cold water inlet and the lower port, 14, is the hot water inlet. The compound valve, 15, has two crown disks, 15¹, 15², respectively,

in which the fingers, 15^a, are reverse and obverse, as shown in Fig. 3, the disks and fingers being neatly ground into their respective ports to make a close, sliding fit. The integral valve stem extends above and below said valves, the upper part, 16, connecting with a rubber diaphragm, 17, and the lower part, 18, connecting with another diaphragm, 19, as shown. The diaphragm, 17, is held in place by the flange of a connecting piece, 20, and by the upper edge of the neck, 21, on the upper chamber, by means of a nut, 22, or in any preferred manner, while the diaphragm, 19, is held in place between the lower edge of the neck, 23, on the lower chamber and a spring case, 24, which is screwed on said neck.

24^a is an air hole. A helical spring, 25, presses upwardly against a flanged nut, 26, which is screwed on the lower valve stem, 18, to hold the diaphragm in position: a screw plug 27, having a square head 27^a is adjustably placed in said spring case.

The connecting piece, 20, screws into a convex body 28 having a flange, 28^a, which supports the air chamber, 29, and the water cylinder or case, 30, for conveying the water upwardly and out through the outlet, 30^a, said cylinder being provided with an integral annular flange, 30^b, at its lower end, and an inlet, 30^c, for the water.

The air chamber, 29, is made of thin metal, preferably brass or copper, a series of tubes, 29¹, 29², 29³, passing therethrough laterally and fastened in the periphery of the air chamber by soldering or otherwise, to act as braces and for the passage of the mixed water which enters the inlet, 30^a, and passes out upwardly through the outlet. A flange, 31, is fastened to the lower edge of said air chamber. A series of holes are drilled through said flange to align with holes in the flanges, 30^b, and 28^a, into which screws, 32, are inserted for holding and clamping the said air chamber, the water cylinder and the rubber diaphragm, 33 together. An extension, 16^a of the upper valve stem, 16 is threaded for the reception of a flanged nut, 34, the diaphragm 17 being centrally held in an operative position between the flange, 16^a, and said nut, 34. The upper end of the valve stem extension enters a flanged stud, 35, having a threaded stud, 35^a upon which a nut, 36, screws, the diaphragm, 33, being centrally held between the said two parts, as shown. An air hole, 20^a, is drilled

through the wall of the connecting piece, 20. Two plug caps, 38, 39 respectively act as guides for the stems, 4¹ and 8¹, respectively of the check valves, and also afford a means for inserting or removing the check valves from the valve body. A curved tube, 40, screwed into the outlet, 11, of the inner chamber, 10, conveys the water from the valve body, 1, upwardly into the water cylinder, where it connects with the inlet, 30^a, by means of an elbow union, 41, as shown in Fig. 4.

The operation is as follows: Hot and cold water supply pipes—not shown—are connected up with the valve body, and when the water is turned on, the supply is adjusted by the screw plug, 27, which presses upwardly against the spring, 25, this in turn pressing upwardly against the lower nut on the valve stem whereby the compound valve is operated, said valve opening and closing, one or the other of the hot or cold water ports, and when the desired temperature of the water has been reached at the outlet, that degree will be maintained automatically and instantly in the following manner: If the hot water should become cooler, the temperature of the mixed water, passing upwardly through the narrow, annular space between the cylinder and air chamber and through the lateral tubes in the air chamber, will be proportionately lowered, the confined air within the air chamber will contract and with the aid of the spring, 25, the compound valve will be pushed upward whereby the cold water is closed off and an excess of hot water is turned on in exact proportion to the difference in the temperature. If the hot water should become hotter than the device was set for, the reverse operation would take place; that is, the mixed water would rise in temperature whereby the confined air in the air chamber is expanded, the diaphragm, 33, will be depressed by the valve stem against the action of the spring, 25, the hot water be shut off and an increased quantity of cold water be turned on until the balance between the compressed air and the compressed spring was reached. This action is so rapid, owing to the construction of the device, that a few degrees variation of the water at the outlet will immediately affect the adjustment or balance which is automatically controlled by the compound valve sliding in the inner chamber, 10, as described.

Briefly stated, the spring, 25, raises the compound valve and presses upwardly against the confined air in the air chamber, and when said air is caused to expand, it presses the valve downwardly against the spring, 25.

What I claim is—

1. In an equalizing valve for water, a valve body having separate inlets for hot and cold water, respectively, an inner cham-

ber communicating with the said inlets, a double acting valve controlling inlet ports in said inner chamber, a superimposed water cylinder connected to said valve body and in communication with said inner chamber, an air chamber positioned in said water cylinder, open transverse tubes through said air chamber, a diaphragm closing one end of said air chamber, mechanical means for pressing said valve in an upward direction and a valve stem upon said valve having one end thereof engaging said diaphragm.

2. In an equalizing valve for hot and cold water, a double acting valve, vertically mounted in an inner chamber through which the hot and the cold water passes, an adjustable spring pressing upwardly against the valve stem of said double acting valve adapted for positioning the valve for a delivery of water at a predetermined temperature, a water cylinder having an inlet at its base and an outlet at its apex, a pipe communicating between said inner chamber and inlet, said water cylinder inclosing an air chamber, a flexible diaphragm closing one end of said air chamber, transverse water pipes through said chamber, and means centrally mounted in said diaphragm for pressing the valve stem of said double acting valve downwardly for closing off the hot water when the confined air in said air chamber is expanded.

3. In a valve device, a valve casing having an inner chamber, hot and cold water inlet chambers at opposite sides thereof and said inner chamber communicating at its bottom and top respectively with said hot and cold water inlet chamber, a vertically movable double acting valve in said inner chamber, oppositely extending stems upon said valve, an adjustable spring contacting the free end of said lower stem adapted for predeterminedly positioning the valve, a water cylinder mounted upon said casing with a bottom inlet and a top outlet, a pipe connecting said inlet and inner chamber, an air container within said cylinder, transverse water pipes through said container, a diaphragm closing the bottom of said container and the upper stem engaging said diaphragm and adapted for movement upon a change in temperature of the air in said container.

4. In a valve device, a valve casing having an inner chamber, hot and cold water inlet chambers at opposite sides thereof, and said inner chamber communicating at its bottom and top respectively with said hot and cold water inlet chambers, a vertically movable double acting valve in said inner chamber, oppositely extending stems upon said valve, an adjustable spring contacting the free end of said lower stem adapted for predeterminedly positioning the valve, said casing having a terminal bottom cham-

ber, an adjusting plug closing the bottom of said last named chamber and a diaphragm closing the top thereof and positioning said spring therebetween, said casing also having 5 a top chamber, a diaphragm closing said top chamber and secured substantially centrally to said upper stem, said casing provided with air ports communicating with said top and bottom chambers, a water cylinder mounted 10 upon said casing, a bottom inlet and a top outlet for said water cylinder, a pipe connecting said inlet and inner chamber, an air container within said cylinder, transverse

water pipes through said container, a diaphragm closing the bottom of said container 15 and the upper stem engaging said diaphragm and adapted for movement upon a change in temperature of the air in said container.

Signed at the city, county, and State of 20 New York this 15th day of January A. D. 1912.
